New York, N. Y., a corporation of New
York

Application April 26, 1950, Serial No. 158,268

6 Claims. (Cl. 121—46.5)

1

This invention relates to a servo-mechanism of the electro-hydraulic type.

A principal object of the invention is to provide a servo control valve wherein an electrical signal is converted to a proportional hydraulic response with a minimum of distortion, a maximum of sensitivity and linearity of response, and an extremely short reaction time, for the control of aircraft and guided missiles, for positioning of heavy artillery and radar antennae, for controlling operations in nuclear and X-ray processes, where human presence would be dangerous, or for other similar purposes.

Another object of the invention is to provide such a valve having a large hydraulic amplification power thereby permitting the use of a relatively small electrical control signal and small electrical actuators.

Another object is to provide an electro-hydraulic servo-mechanism the operation of which is independent of fluctuations or changes in the supply pressure of the pressure fluid within very broad limits.

A further object is to provide an electro-hydraulic valve that is simple as to its parts, light in weight, and readily adjustable to respond to various reaction times, control impulses, and output requirements.

These and other objects and advantages are provided by an electro-hydraulic valve comprising a balanced valve port controlling spool and an electro-hydraulic actuator to vary the force acting on the balanced spool whereby the valve ports are proportionally controlled in response to the magnitude of an electrical control signal.

The invention will be more particularly described with reference to the illustrative embodiments of the invention shown in the accompanying drawings, in which:

Fig. 1 is a longitudinal section illustrating a servo-mechanism constructed in accordance with the principles of the invention;

Fig. 2 is a sectional view on line 2—2 of Fig. 1; and

Fig. 3 is a longitudinal sectional view of a modified form of the invention.

Referring to the drawings, 8 is the valve body having pressure fluid ports 9 and 10 and drain or sump port 11. Ports 9 and 10 connect the valve with the mechanism to be operated, which is shown by way of illustration as a double acting piston 12, comprising a cylinder 13, and a piston 14, having operating faces 15 and 16 of unequal area. Face 15 has twice the area of face 16. Conduit 17 connects valve port 9 to the cylinder

2

between piston face 15 and the adjacent end of the cylinder, while conduit 18 connects valve port 10 to the pressure supply line 19 and to the other end of cylinder 13.

5 A valve spool 20 is slidably carried within the valve body 8 and comprises a cylindrical body having two control channels or annular grooves 21 and 22. A cantilever spring 23 provided with an adjustment screw 24 biases the spool toward the right. Preferably the cantilever spring has a linear force-deflection relationship.

An annular groove 25, within the valve body, connects spool channels 21 and 22, when the spool is centered in the valve body as shown in the drawings, providing orifices 26 and 27 which control the flow of pressure fluid within passages 28, 29 and 30. Thus with the spool centered in the valve body orifices 26 and 27 provide equal resistance to the flow of pressure fluid between supply passage 28, and passage 29, and between passage 29 and drain passage 30. Under these conditions the pressure in passage 29 will be the mean of the supply pressure in passage 28 and the drain pressure in passage 30. Piston 14 will be at rest, as the pressure fluid in passage 29 is vented to the large side 15 of the piston 14 and the supply pressure is vented to the small side 16, of the piston and the hydraulic forces acting on the piston are balanced.

10 30 Lateral movement of the spool 20 will unbalance the flow resistance at orifices 26 and 27, formed by annular grooves 21, 22 and 25, and the pressure in passage 29 will no longer be the mean of the supply and drain pressures. Thus movement of spool 20 toward the left will open orifice

20 35 40 45 50 27 and pressure fluid from supply conduit 19 will be vented directly to the large side 15 of piston 14 through passage 28, orifice 27, passage 29, and conduit 17. Concurrently with the opening of orifice 27, orifice 26, vented to the drain passage 30, will be closed, and piston 14 will move toward the right with a velocity proportional to the area of opening of orifice 27.

Conversely, if the spool is moved toward the right from its centered position, orifice 27 will close shutting off the supply of pressure fluid to the large side 15 of piston 14 and orifice 26 will be opened allowing pressure fluid on the large side of the piston, in conduit 17 and in passage 29 to be vented to the drain port 11, and piston 14 will move toward the left with a velocity proportional to the area of opening of orifice 26.

When external axial forces are applied to the piston 12, the reactions described above will be slightly modified. For instance, with the piston

at rest, the pressure forces must be unbalanced to produce reaction force. This is accomplished by an extremely small departure of the spool 20 from its centered position in orifice 25. Then orifices 26 and 27 will differ in flow restriction to the extent that the pressure in chamber 29 can change to the value necessary to provide the pressure-force unbalance. Also, external load will affect the velocity of piston motion proportional to the position of spool 20. This results from the change in pressure difference at either orifice 26 or 27 depending upon the axial load and causes a different flow rate or piston velocity for a particular opening of either orifice.

Lateral displacement of the valve spool 20 is brought about by changes in the fluid pressure acting on the head 31 of the spool against the force of the cantilever spool biasing spring 23. The pressure of the pressure fluid acting on spool head 31 is controlled by an electric signal through the electro-hydraulic actuator 32, comprising a fluid pressure nozzle 33, a pressure reaction plate 34 and an electric motor 35.

Nozzle 33 has a restricted opening 37 at one end and at the other forms an annular orifice between its tip and pressure reaction plate 34. A chamber 38 lies between orifice 36 and the restricted opening 37. Pressure fluid is supplied to chamber 38 of the nozzle through passage 39 provided with a flow restrictor 40. Pressure fluid thus supplied to chamber 38 passes through the restricted opening 37 and, provided that spool 20 has no instantaneous velocity, creates in chamber 41 an equal pressure which acts against the head 31 of spool 20 and a spool deflection proportional to the pressure within nozzle chamber 38 is obtained. Coinstantaneously the pressure fluid in chamber 38 issues from orifice 36 into chamber 42 that is nominally substantially filled with liquid and is provided with an upper drain passage 43.

The rate of flow of pressure fluid from chamber 38 and sump chamber 42 is determined by the pressure difference between the chambers. This pressure difference is exerted on the area of the reaction plate 34 equal to the tip area of nozzle 33. As the plate area for the full range of motion of the plate remains essentially constant, then the pressure in chamber 38 is always proportional to the force on the reaction plate 34. It is the function of motor 35 to produce on the plate a force proportional to an electrical signal applied to the motor.

The electric motor 35 of the electro-hydraulic actuator comprises: a coil 44 having terminals 45; pole pieces 46 and 47; permanent magnets 48 and 49; armature 50, the lower end of which forms the reaction plate 34; and armature biasing spring 51.

The permanent magnets 48 and 49 of the motor are oriented so that they contribute toward the maintenance of dissimilar poles of pole pieces 46 and 47. An armature mount 52 provides a base for cantilever mounting of the armature 50. The armature extends through the air gap 53 between the pole pieces 46 and 47. Armature 50 is constructed of low hysteresis, magnetic resilient material and has a relatively low spring rate at the air gap 53 by virtue of its cantilever mounting 52, and is free to move in the air gap through an arc subtended by the pole piece 47 and orifice 36.

A biasing spring 51 is secured at one end to the reaction plate 34 and at the other end to a biasing spring mount 54, having a spring force 75

adjusting screw 55. The screw 55 is threaded in a bushing 56 of low permeability to reduce the tendency to form a secondary magnetic circuit through the biasing spring 51. Biasing spring 51 has a force-deflection ratio or spring rate equal and opposite to the armature rate within the operating range in the air gap 53. The armature rate is the sum of the force-deflection ratio of the armature due to its resilience and the force-deflection ratio resulting from the action of the magnetic field on the armature. The operating range is centered at the center of the air gap and extends approximately half way from the center towards both poles; in this range the armature rate is substantially linear. It will be observed that without the biasing spring the armature would not remain in its centered position in the air gap 53, but would snap toward one of the pole pieces 46 or 47. This is due to the decrease in magnetic reluctance between the armature and the pole piece as the armature moves toward that pole piece while the magnetic reluctance between the armature and the other pole piece increases. Thus the flux density in the air gap 53 increases as the armature moves from the center toward either pole piece. The resultant forces acting on the armature within the operating range are counterbalanced by the biasing spring, since its spring rate is equal and opposite to the armature rate in the operating region, the spring rate and the armature rate cancel, leaving no rate within the operating range of the air gap and the armature can be positioned at any point within the operating range without the application of any substantial force. Wherever the armature is positioned in the operating range, it will tend to remain because the magnetic and spring forces are always in balance. This effect, while not essential to the operation of the valve, is of importance, as will be shown hereinafter, as it permits the operation of the electrohydraulic actuator independently of fluctuations or changes in the supply pressure of the pressure fluid within very broad limits.

The coil 44 actuates the armature 50 by changing the flux density within the air gap 53. In the initial operation of the servo valve, the valve spool is centered in the valve body before any current is applied to the coil 44. The spool is centered by means of the armature biasing spring tension adjustment screw 55, which changes the biasing spring force. If this force is increased, the armature is forced toward the nozzle orifice, restricting the flow of pressure fluid from the orifice and creating a pressure in chambers 38 and 41 causing a linear displacement of the spool 20 against the cantilever spring 23. As the pressure rises, the pressure force on the reaction plate 34 increases until a balance with the new biasing spring force is reached.

The coil 44 may be of the push-pull type wherein the magnetic force upon the armature will have magnitude and sense proportional to the differential current between the two windings of the coil, or a simple double-ended coil may be employed. In each instance an electrical signal applied to the coil will vary the flux density in the air gap and armature 50 will move either toward or away from the orifice 36 depending upon the sense of the current applied, and the pressure within chambers 38 and 41 will rise or fall substantially proportionally to the coil current, producing a relative movement in valve spool 20. This becomes apparent upon consideration of all of the forces acting on the

armature and its extension in the direction of the spool axis. These forces are: the force due to the current in the coil 44; the force of the biasing spring 51; the force created by the pressure in chamber 38; and that due to the position of the armature in the air gap. As hereinbefore described, the spring rate of the biasing spring is equal and opposite to the armature rate within the operating range and they cancel; the forces left that affect the armature are the forces created by the pressure in chamber 38, the current in the coil and the biasing spring. With no current in the motor coil the force of the pressure in chamber 38 tending to move the armature toward the right and the force of the biasing spring acting in the opposite direction will reach equilibrium. The armature will remain stationary in an equilibrium position and the pressure within the chambers 38 and 41 will be constant. When an electric current is applied to the motor coil, the force of the armature will change and the pressure in chambers 38 and 41 will rise or fall proportionally to the coil current.

The pressure in chamber 38 will not be affected however by changes in the supply pressure of the pressure fluid within wide limits. Any change in supply pressure will change the flow through orifice 40 and annular orifice 36. Hence the distance between nozzle tip 33 and the reaction plate 34 must change in order that the pressure in chamber 38 remain constant as the flow changes. But this distance change does not affect the pressure-force balance on the reaction plate and since the motor force is independent of the position of the plate due to cancellation of the armature and spring rates, no change of pressure in chamber 38 will occur as supply pressure changes.

The fact that the reaction plate 34 has changed position to compensate for variations in the fluid supply pressure does not affect the overall response of the servo-mechanism; a given input signal will actuate the armature 50, and the reaction plate which is the extension of the armature, in the same way regardless of its position in the operating range because of the balance between the armature rate and the biasing spring rate.

In order to prevent oscillation of the spool due to flow reaction forces on the spool 20 at orifices 26 and 27, restriction 37 is provided between chambers 38 and 41 to damp the flow of pressure fluid to and from chamber 38.

Fig. 3 of the drawings illustrates a modified form of the invention wherein an electric motor 57 having a rotatable armature 58 is utilized to actuate the reaction plate 34. Like parts throughout the illustrative embodiments have similar character designations. In operation of the device shown in Fig. 3, electrical signals are supplied to the motor terminals 59 and the magnetic torque produces a force tending to rotate the armature 58, and the pressure reaction plate 34 secured to the armature shaft 60; the displacement of the plate 34 along the axis of the valve spool 20 being proportional to the applied current.

From the foregoing description it will be seen that the present invention provides a servo control mechanism wherein an electrical signal is converted to a proportional hydraulic response with a minimum of distortion, and a maximum of sensitivity and linearity of response.

It will be evident that various modifications may be made in the form of the valve without departing from the scope of the invention. For

example, the valve may be of the multiple port type and the mechanism to be operated may advantageously be of the bellows type instead of the reciprocating piston shown by way of illustration in the drawings.

I claim:

1. An electro-hydraulic servo valve comprising a valve body having pressure fluid control ports, a valve member movably mounted in a bore in said body for controlling the flow of fluid through said ports, a pressure fluid chamber, a restricted orifice connecting the pressure fluid chamber and the bore in the valve body, means biasing said valve member in the direction of said restricted orifice, means for introducing pressure fluid directly into said chamber, and means for varying the pressure in said chamber, comprising an orifice communicating with said chamber and in fixed position relative thereto, a pressure reaction member positioned adjacent said orifice, spring means biasing said pressure reaction member in the direction of said orifice, and an electric motor for varying the force of said pressure reaction member in response to an electric signal applied to said motor.

2. An electro-hydraulic servo valve comprising a valve body having pressure fluid control ports, a valve member movably mounted in said body for controlling the flow of fluid through said ports, a pressure fluid chamber in actuating relationship to said valve member, means biasing said valve member in the direction of said chamber, means for introducing pressure fluid into said chamber and means for varying the pressure in said chamber comprising an orifice communicating with said chamber, and means for restricting the flow of pressure fluid from said orifice in response to the magnitude of an electrical control signal, said means comprising a pressure reaction plate adjacent said orifice, an electro-magnetic motor having a permanent magnetic field with a superimposed variable magnetic field produced electromagnetically thereon for varying the force of said plate, a spring producing a force balance with the attraction of that component of the total magnetic field which is due to the permanent magnet's magneto-motive force, the rate of said spring being such as to effect said force balance, whereby the net force of the pressure reaction plate is varied in response to an electric signal applied to said motor.

3. A servo valve, electro-hydraulic means for actuating the valve, said means comprising a fluid pressure chamber in actuating relationship to the valve, means biasing the valve in the direction of the fluid pressure chamber, and means for varying the pressure in said chamber comprising an orifice communicating with said chamber, and means for restricting the flow of pressure fluid from said orifice in response to the magnitude of an electrical control signal, said means comprising a pressure reaction plate adjacent said orifice, an electro-magnetic motor having a permanent magnetic field with a superimposed variable magnetic field produced electromagnetically thereon for varying the force of said plate, a spring producing a force balance with the attraction of that component of the total magnetic field which is due to the permanent magnet's magneto-motive force, the rate of said spring being such as to effect said force balance, whereby the net force of the pressure reaction plate is varied in response to an electric signal applied to said motor.

4. In an electro-hydraulic servo valve compris-

ing a valve body having pressure fluid control ports, and a valve member movably mounted in a bore in said body for controlling the flow of fluid through said ports; a pressure fluid chamber, a restricted orifice connecting the pressure fluid chamber and the bore in the valve body, means biasing said valve member in the direction of said restricted orifice, means for introducing pressure fluid directly into said chamber, and means for varying the pressure in said chamber comprising an orifice communicating with said chamber and in fixed position relative thereto and means for restricting the flow of pressure fluid from said orifice, said means comprising a pressure reaction plate adjacent said orifice, an oscillatory armature attached to said plate, spring means biasing said armature in the direction of said orifice, and an electro-magnetic motor for varying the force of said armature in response to the magnitude of an electrical signal applied to said motor.

5. In an electro-hydraulic servo valve comprising a valve body having pressure fluid control ports, and a valve member movably mounted in a bore in said body for controlling the flow of fluid through said ports; a pressure fluid chamber, a restricted orifice connecting the pressure fluid chamber and the bore in the valve body, means biasing said valve member in the direction of said restricted orifice, means for introducing pressure fluid directly into said chamber, and means for varying the pressure in said chamber comprising an orifice communicating with said chamber and in fixed position relative thereto and means for restricting the flow of pressure fluid from said orifice, said means comprising a pressure reaction plate adjacent said orifice, a rotatable armature attached to said plate, spring means biasing said armature in the direction of said orifice, and an electro-magnetic motor for varying the force of said armature and pressure reaction plate in response to the magnitude of an electrical signal applied to said motor.

6. An electric hydraulic servomechanism comprising a body portion, a pressure responsive member carried by said body portion, a pressure fluid chamber in actuating relationship to the pressure responsive member, means biasing said pressure responsive member in the direction of said chamber, and means for varying the pressure in said chamber comprising an orifice communicating with said chamber, and means for restricting the flow of pressure fluid from said orifice in response to the magnitude of an electrical control signal, said means comprising a pressure reaction plate adjacent said orifice, an electro-magnetic motor having a permanent magnetic field with a superimposed variable magnetic field produced electromagnetically thereon for varying the force of said plate, a spring producing a force balance with the attraction of that component of the total magnetic field which is due to the permanent magnet's magneto-motive force, the rate of said spring being such as to effect said force balance, whereby the net force of the pressure reaction plate is varied in response to an electric signal applied to said motor.
